UNITED STATES PATENT OFFICE.

ELBERT L. HYDE, OF PITTSBURGH, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,142,565.

Specification of Letters Patent.

Patented June 8, 1915.

Application filed July 6, 1914. Serial No. 849,303.

To all whom it may concern:

Be it known that I, ELBERT L. HYDE, a resident of Pittsburgh, in the county of Allegheny and State of Pennsylvania, have 5 invented a new and useful Improvement in Garment-Stays, of which the following is a specification.

This invention relates to garment stays, and particularly to wire stays such as are 10 used in corsets or other like articles of wearing apparel.

The object of the invention is to provide a strong and durable stay which contains a 15 long length of wire in a stay of given dimensions, which is very stiff and has a high degree of resistance to bending strains, particularly in the edgewise direction, and which is not liable to take a permanent set when subjected to short bends.

20 The invention comprises the stay herein-after described and claimed.

In the drawings Figure 1 represents a plan view on an exaggerated scale of one 25 face of a stay embodying the invention; and Fig. 2 is a similar view of another form of stay.

The stay shown in the drawings is formed of wire and preferably is formed of a plurality of wires 1, two being shown, which 30 are bent back and forth in a sinuous form from edge to edge of the stay to form a series of alternately disposed loops or eyes 2, lying along the edges of the stay, and a series of transversely extending connecting 35 portions or crossings 3. Preferably the crossing portions of each wire are inclined to a true transverse line across the stay, all of the crossing portions in the same wire being inclined in the same direction and being 40 substantially parallel from edge to edge of the stay. Also, the crossing portions of the two wires are inclined in opposite directions, as shown in the drawings. Furthermore, the crossing portions of the different 45 wires of the stay are interwoven or interlaced, that is, they pass under and over each other, so that the complete stay is a fairly close network of wires extending in two diagonal directions across the stay.

50 The crossing portions of the two wires may cross each other any number of times, depending upon the dimensions of the wire and the width of the stay, as will be observed by comparison of Figs. 1 and 2, 55 which illustrate stays of different widths.

Also, the open loops or eyes in the two wires along the same edge of the stay may be interlaced with each other, as shown at 4 in Fig. 1, or may merely overlap each other slightly, as shown at 5 in Fig. 2. The form 60 shown in Fig. 1 is quite stiff in the edgewise direction and is therefore especially suitable for uses in which edgewise bending is undesirable, as for a corset clasp member, but the form shown in Fig. 2 is also very 65 resistant to bending strains, particularly in the edgewise direction.

The stay shown contains a long length of wire in a stay of given dimensions and the wires are closely interlocked with each other 70 so that they are held against relative movement. Consequently, the stay is very resilient, durable and strong and is not liable to take a permanent set when subjected to short bends.

75 What I claim is:—

1. A garment stay, comprising a plurality of wires bent back and forth in opposite directions to form a series of transversely extending crossing portions, the crossing portions of the wire being inclined to a true transverse line, all of the crossing portions in each wire being substantially parallel from edge to edge of the stay. 80

2. A garment stay, comprising a plurality of wires bent back and forth in opposite directions to form a series of transversely extending crossing portions, the wires being interlaced or interwoven with each other, the crossing portions of the wire being inclined to a true transverse line, all of the crossing portions in each wire being substantially parallel from edge to edge of the stay. 85

3. A garment stay, comprising a plurality of wires bent back and forth in opposite directions to form a series of transversely extending crossing portions which are inclined to a true transverse line, all of the crossing portions in each wire being substantially parallel from edge to edge of the stay, the crossing portions of different wires being inclined in different directions. 90

4. A garment stay, comprising a plurality of wires bent back and forth in opposite directions to form a series of transversely extending crossing portions which are interlaced or interwoven with each other, the crossing portions of each wire being inclined to a true transverse line and substan- 105

tially parallel to each other, the crossing portions of different wires being inclined in different directions.

5. A garment stay, comprising two wires bent back and forth in sinuous form from edge to edge of the stay to form a series of alternately disposed loops or eyes lying along the edges of the stay and a series of transversely extending crossing portions, the 10 two wires being interlaced or interwoven with each other, the crossing portions in each wire being inclined to a true transverse line and substantially parallel to each other.
- 15 6. A garment stay, comprising two wires bent back and forth in sinuous form from

edge to edge of the stay to form a series of alternately disposed loops or eyes lying along the edges of the stay and a series of transversely extending crossing portions, 20 the two wires being interlaced or interwoven with each other, the crossing portions in each wire being inclined to a true transverse line and substantially parallel to each other, the crossing portions of the two wires being 25 inclined in opposite directions.

In testimony whereof, I have hereunto set my hand.

ELBERT L. HYDE.
